CLAIM

The ornamental design for a laptop computer, as shown and described.

DESCRIPTION

FIG. 1 depicts an opened front perspective view of a laptop computer;

FIG. 2 depicts an opened top plan view thereof;

FIG. 3 depicts a closed front lower elevation view thereof;

FIG. 4 depicts a closed rear elevation view thereof;

FIG. 5 depicts a closed right elevation view thereof;

FIG. 6 depicts a closed left elevation view thereof;

FIG. 7 depicts an opened bottom plan view thereof; and,

FIG. 8 depicts a closed top plan view thereof.

The broken lines depicting the display and logo disposed on the hinged upper portion of the laptop computer and the keyboard disposed on the lower portion of the laptop computer are included for additional clarity and for the purpose of illustrating the article and form no part of the claimed design.

The broken lines depicting the input, output, and peripheral device ports disposed on the rear, left side, and right side of the lower portion of the laptop computer are included for additional clarity and for the purpose of illustrating the article and form no part of the claimed design.

The broken lines depicting the battery compartment cover and feet disposed on the bottom of the lower portion of the laptop computer are included for additional clarity and for the purpose of illustrating the article and form no part of the claimed design.
